(57) **CLAIM**

The ornamental design for a set of microphone, receiver and charging cases, as shown and described.

DESCRIPTION

FIG. 1 is a perspective view of a microphone of a set of microphone, receiver and charging cases of FIG. 39 showing my new design, shown separately for ease of illustration; FIG. 2 is another perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; FIG. 8 is a bottom plan view thereof; FIG. 9 is a perspective view of a receiver of the set of microphone, receiver and charging cases of FIG. 39, shown separately for ease of illustration; FIG. 10 is another perspective view thereof; FIG. 11 is a front elevational view thereof; FIG. 12 is a rear elevational view thereof; FIG. 13 is a left side elevational view thereof; FIG. 14 is a right side elevational view thereof; FIG. 15 is a top plan view thereof; FIG. 16 is a bottom plan view thereof; FIG. 17 is a perspective view of a first charging case of the set of microphone, receiver and charging cases of FIG. 39, shown separately for ease of illustration and in an open state; FIG. 18 is another perspective view thereof; FIG. 19 is another perspective view thereof; FIG. 20 is a front elevational view thereof; FIG. 21 is a rear elevational view thereof; FIG. 22 is a left side elevational view thereof; FIG. 23 is a right side elevational view thereof; FIG. 24 is a top plan view thereof; FIG. 25 is a bottom plan view thereof;

(Continued)

FIG. 26 is a perspective view of the microphone, the receiver, and the first charging case of the set of microphone, receiver, and charging cases of FIG. 39, shown in a state of use;

FIG. 27 is a perspective view of the first charging case of the set of microphone, receiver, and charging cases of FIG. 39, shown separately for ease of illustration and in a closed state;

FIG. 28 is a perspective view of a second charging case of the set of microphone, receiver and charging cases of FIG. 39, shown separately for ease of illustration and in an open state;

FIG. 29 is another perspective view thereof;

FIG. 30 is another perspective view thereof;

FIG. 31 is a front elevational view thereof;

FIG. 32 is a rear elevational view thereof;

FIG. 33 is a left side elevational view thereof;

FIG. 34 is a right side elevational view thereof;

FIG. 35 is a top plan view thereof;

FIG. 36 is a bottom plan view thereof;

FIG. 37 is a perspective view of the microphone, the receiver, and the second charging case of the set of microphone, receiver, and charging cases of FIG. 39, shown in a state of use;

FIG. 38 is a perspective view of the second charging case of the set of microphone, receiver, and charging cases of FIG. 39, shown separately for ease of illustration and in a closed state; and,

FIG. 39 is an exploded view of the set of microphone, receiver, and charging cases, showing my new design.

The broken lines in the drawings depict portions of the set of microphone, receiver and charging cases that form no part of the claimed design. Additional broken lines showing a microphone in FIG. 26 illustrate environmental subject matter and form no part of the claimed design.
